UNITED STATES PATENT OFFICE.

JOHN J. MANGEL AND HENRY J. WILLEMS, OF KENOSHA, WISCONSIN, ASSIGNORS TO
THE SIMMONS MANUFACTURING COMPANY, OF KENOSHA, WISCONSIN, A CORPO-
RATION OF WISCONSIN.

BED FABRIC.

1,100,384.

Specification of Letters Patent. Patented June 16, 1914.

Application filed February 9, 1914. Serial No. 817,412.

To all whom it may concern:

Be it known that we, JOHN J. MANGEL and HENRY J. WILLEMS, citizens of the United States, residing in the city of Kenosha, county of Kenosha, and State of Wisconsin, have invented certain new and useful Improvements in Bed Fabrics, of which the following is a full and complete description.

10 Our invention relates particularly to wire fabrics employed in beds and couches, and refers more particularly to a link fabric which is adapted to be connected to a supporting frame by coiled springs or other 15 resilient means.

Among the salient objects of the invention are to provide a construction in which the links comprising the fabric are so arranged and adapted to be connected to the supporting springs as to tension the fabric both longitudinally and transversely; to provide a wire bed-fabric which is capable of being folded in either direction, and will at the same time be sufficiently stiff, both longitudinally and transversely, properly to support the weight of a person occupying the bed or couch; to provide, in a bed fabric of the class described, means for connecting up the various chains of links forming the fabric which will enable the fabric to be assembled in an extremely rapid and secure manner, and in such a way as to make it practically impossible for any of the links composing the fabric to become accidentally 35 displaced; to provide, in a fabric of the class described, a form of construction which will permit the application of any required degree of tension upon the various chain strands forming the fabric; to provide a 40 construction of bed fabric in which the spring tension applied to the longitudinal chain members composing the fabric is transmitted to the cross links connecting the longitudinal members in such a way as to 45 impart lateral, as well as longitudinal, stiffness, to the fabric; to provide, in a fabric of the class described, an improved chain-link construction which will display marked superiority in its mechanical design and economy of manufacture, and to provide an improved construction of the general character referred to.

Our invention consists in the matters hereinafter referred to, and more particularly

described in connection with the accompanying drawings, in which—

Figure 1 represents a preferred form of bed fabric constructed in accordance with our invention, parts being broken away and shortened up in order to lessen the size of the drawing. Fig. 2 is a sectional view taken along the line 2—2 in Fig. 1; and Fig. 3 is a section taken along the line 3—3 in Fig. 1.

Referring to Fig. 1, it will be seen that the stationary frame to which the bed fabric is adapted to be connected is composed of a pair of lateral head and foot members 1 and 2, which are braced and connected together by two or more longitudinal strut bars 3, only one of which is shown in the drawings. The longitudinal chains are composed of a series of links 4, all of which are alike and formed of a length of wire of suitable cross-sectional area, bent in the form shown. As shown in the drawings, each link is provided with an enlarged eye-loop at one end, its two sides approach one another and meet at the other end of the link, and are there bent to form a hook, which engages the eye of the adjacent link. The chains are preferably formed in suitable lengths before being assembled together to form the bed fabric.

An important feature of our invention is the manner of arranging the longitudinal chains in the fabric with the links alternately pointing in different directions, the advantages of which will hereinafter appear.

As just described, the longitudinal chains are arranged to point in different directions alternately. The desired tension and spring effect is furnished by a series of helical springs 5, one of which is connected to the hook of the link at the extremity of each of the longitudinal chains. Since the chains are arranged alternately in reverse directions, this arrangement brings the springs connected to adjacent chains alternately to either end of the fabric. The helicals are hooked into engagement with the cross members 1 and 2 in a self-evident manner. The chains themselves are connected together by means of the cross links 6, each of which is a short length of wire having each end bent up to form a hook which engages the eye-loop in one of the links composing the longitudinal chains, each cross-link connecting

the eyes of diagonally-contiguous links in adjacent longitudinal chains of the fabric. It is evident that, owing to the peculiar method of arranging the longitudinal chains alternately in reverse directions across the fabric, the cross links 6 will be placed under tension owing to the longitudinal pull of the helicals 5. The pull of the springs in different directions applied to the adjacent 5 reversed chains of the fabric causes the cross-links to assume an oblique or angular position with reference to the longitudinal chains. It will be seen also that the ends of the chains adapted to be anchored to one end 10 of the frame project beyond the ends of the alternate chains anchored to the other end of the bed frame. This results in a construction which is laterally tensioned by means of the indirect action of the springs 15 upon the cross links, as well as being tensioned longitudinally by the springs themselves; but it does not introduce any difficulties in the way of folding the bed fabrics along one or more longitudinal lines, as is 20 frequently desirable in case of a folding bed or couch. In order to maintain the outermost chains at the sides in their proper positions and to furnish an anchor for the outermost cross links 7, we provide a longitudinal strap 8, which is suitably apertured 25 for the cross links 7. The strap 8 is resiliently connected to the cross members 1 and 2 by means of pairs of helical springs 9, which allow the strap to yield slightly under 30 the pull of the cross links 7.

In its broader aspects, the invention is not limited to the details of construction described except as specified in the appended claims.

40 We claim as our invention—

1. A fabric composed of a series of link chains arranged in substantial parallelism, each chain comprising a series of links having at one end an eye and at the opposite 45 end a hooked portion engaging the eye of the adjacent link whereby the links point in the same direction, and a second series of chains alternately disposed between the chains of the first series and similarly 50 formed but having their links extending in opposite direction to the links of the first chain, and cross links connected to said chains.

55 2. A fabric composed of a series of longitudinal link chains arranged in substantial parallelism, each chain comprising a series of links having at one end an eye and at the opposite end a hooked portion engaging the eye of the adjacent link whereby 60 the links point in the same direction, and a second series of chains alternately disposed between the chains of the first series and similarly formed but having their links extending in the opposite direction to the links of the first chain, and cross links connected to the 65 links of the first chain, and cross links con-

necting said chains, a plurality of the chains of each series projecting beyond the adjacent ends of the other series.

3. A fabric composed of a series of link chains in substantial parallelism, each chain comprising a series of links having at one end an eye and at the opposite end a hooked portion engaging the eye of the adjacent link whereby the links point in the same direction, a second series of chains alternately disposed between the chains of the first series and similarly formed, but having their links extending in the opposite direction to the links of the first chain, and cross links connecting the eyes of diagonally-contiguous 70 links of the adjacent chains of the fabric. 75

4. A fabric composed of a series of link chains arranged in substantial parallelism, each chain comprising a series of links having at one end an eye and at the opposite end a hooked portion engaging the eye of the adjacent link whereby the links point in the same direction, a second series of chains alternately disposed between the chains of the first series and similarly formed but having their links extending in opposite direction to the links of the first chain, and cross links connected to diagonally-contiguous links of said chains, a plurality of the chains of each series projecting beyond the cross links and adjacent ends of the chains of the other series. 80 85

5. A fabric composed of a series of longitudinal link chains arranged in substantial parallelism, each chain comprising a series of links having at one end an eye and at the opposite end a hooked portion engaging the eye of the adjacent link, whereby the links point in the same direction, a second series of chains alternately disposed between the chains of the first series and similarly formed, but having their links extending in the opposite direction to the links of the first chain, the ends of the chains in one series being adapted to receive tension in one direction, and the opposed ends of the chains of the other series being similarly adapted to receive tension in an opposed direction, and cross links engaging the eyes of diagonally-contiguous links in the adjacent chains. 90 95 100 105

6. A fabric composed of a series of chains, each comprising a plurality of flexibly connected links formed to point in the same direction, a second series of chains alternately disposed between the chains of the first series and similarly formed, but having their links pointing in the opposite direction to the links of the first chains, and oblique cross links engaging the eyes of the diagonally-contiguous links of adjacent chains for maintaining the said chains in position against the application of tension to the opposite ends of the chains in each series. 110 115 120 125 130

7. In a flexible metallic fabric, the combination with a series of link chains arranged in substantial parallelism, of a second series of link chains alternately disposed between the chains of the first series, similar ends of the chains in one series being arranged to receive longitudinal tension, and opposite similar ends of the chains in the other series being arranged to receive tension in the other direction, and cross links connecting the adjacent chains and arranged to transmit said longitudinal pull between the adjacent chains.
8. A bed fabric composed of a transverse row of longitudinal chains composed of a series of links, each link formed of a length of wire shaped to provide a hook at one end and an eye at the other end, each chain having its links arranged so that similar ends of said links point in a similar direction, the adjacent hooks and eyes being in engagement, the several chains of the row being alternately reversed longitudinally to cause the links of adjacent chains to point in dif-
- ferent directions, and cross links having extremities engaging the eyes of the adjacent longitudinal chain links and connecting said chains together.
9. A bed fabric composed of a series of link chains arranged in substantial parallelism, the diagonally-contiguous links of adjacent chains of the series having eyes at their adjacent ends, and cross-links engaging said eyes.
10. In a bed fabric, the combination of a series of longitudinal chains arranged in substantial parallelism, alternate chains of the series being adapted normally to be placed under spring tension applied to the opposed ends of said alternate chains, and cross-members connecting the adjacent chains and adapted to transmit said spring tension.
